UNITED STATES PATENT OFFICE

2,605,759

CLOSURE FOR OVENS

Thomas Esta Phares, Shelbyville, Ind., assignor
to Chambers Corporation, a corporation of Indiana

Application January 13, 1949, Serial No. 70,717

5 Claims. (Cl. 126—190)

1

This invention relates to a closure for ovens, and has particular reference to a means for adjusting the door frame to provide a sealing fit between the door frame and the door.

In order to provide a proper baking atmosphere, ovens must be capable of retaining heat for a long period of time. Heat loss from the oven due to seepage requires the constant application of heat to the oven, thus making the operation of the oven a very costly affair. Additionally, the constant variations of heat within the oven which are an incident to such uneconomical operations make for undesirable baking conditions. For these reasons it is essential to have a tight fit between the oven door and the front of the oven.

In the better grades of stoves it has been customary to form the door and the door frame of castings, and to machine the meeting surfaces to provide as close a fit as possible. However, the door frame is frequently twisted to a slight extent when the screws by which it is secured to the chassis of the stove are tightened, with the result that the machined surfaces do not lie in the same plane and therefore can not form a sealing fit.

In accordance with the present invention, means are provided to adjust the door frame when it is secured to the chassis so that the machined surface, which engages a machined surface of the door when the door is closed, will lie in a single plane. The adjustment of the door frame is made after the frame is secured to the front of the oven, and any additional adjustment necessary to provide a sealing fit with the edges of the door can be made after the door is mounted. Accordingly, nothing can interfere with the proper alignment of the door frame.

The adjustment means of the present invention is simple and inexpensive and is concealed by the outer shell of the oven so that it does not detract from the appearance of the oven.

The structure by which the above advantages are attained will be described in the following specification, taken in conjunction with the accompanying drawing, in which:

Figure 1 is a fragmentary front view of a cooking stove provided with an oven embodying the invention;

Fig. 2 is an enlarged perspective view of the front of the oven with the oven door open;

Fig. 3 is a cross sectional view, taken along the line 3—3 of Fig. 2, but showing the door in closed position; and

Fig. 4 is an enlarged cross sectional view show-

ing the top portion of the door frame with the top portion of the door closed and in sealing relationship with the frame.

In the drawings, the reference numeral 2 indicates a cooking stove having a front 3 and a door 4 closing the front of an oven contained in the stove. The door is hinged at its bottom to a hinge lug 5 and latched at its top edge by means of a handle 6 engaging a latch 7.

10 The door comprises spaced panels 8 and 9 and a casting 10. The casting is of the same shape as the door and fits around the outer edges with one portion 11 projecting between panels 8 and 9. The projecting face of portion 11 is machined, 15 as indicated at 12, to form a smooth flat surface adapted to engage the door frame to form a sealing fit.

The outer surface of panel 8 is preferably coated with porcelain or other suitable material to 20 provide a neat appearance for the exposed surface. The inner panel may be finished in any suitable manner, and is secured in place by means of a plurality of screws 13. The space between panels 8 and 9 is filled with insulation 14, preferably rock wool, but which may be of any other suitable material.

The door frame 15 is a casting which extends around the front edges of the oven and has a portion 18 machined to cooperate with machined 30 surface 12 of the door to form a sealing fit therewith. A plurality of screws 17 secures the door frame to the body front sheet 16 of the stove. Tightening screws 17 frequently cause a slight twisting of casting 15, thereby spoiling the proper 35 alignment of the door frame. In accordance with the teachings of the present invention, screws 17 are screwed only part way into position, and set screws 19 are then adjusted to position the door frame in proper alignment.

40 The set screws are threaded through threaded apertures in casting 15 and the forward end of each screw engages body front sheet 16 of the stove which is rigidly supported from behind by the stove frame, as shown in Figs. 3 and 4. Continued rotation of any set screw, after its forward end is in engagement with the body front sheet, will force the portion of the casting in the area of the particular screw away from the body front sheet. Each screw 19 is tightened until the 45 door frame is properly aligned. Then screws 17 are tightened to hold the door frame in position. Although only two set screws are shown, it will be obvious that any desired number may be used. If it is found that the door frame is not properly aligned, screws 17 may be loosened until the 55

proper adjustment is made, and then tightened again.

An outer shell 20 extends far enough below screws 17 and 19 to conceal them from view when the stove is completely assembled. The outer shell is cut away around the front of the oven to permit the hinged door to move about its hinge.

The oven door is provided at each end with a door stop 21. The door stop is in the form of a flat metal strip shaped in an irregular curve and has one end rigidly secured to door 4, and the other end projecting through a slot 22 in door frame 15. A stop rod 23 is secured to the end of door stop 21 inside the body of the stove, and has a coiled compression spring 24 encircling it between a pair of washers 25 and 26. Top washer 25 is secured to the stove in any suitable manner, and a nut 27 is threaded on the bottom of rod 23 under washer 26 to provide means for adjusting the spring so that door 4 may function properly. When door 4 is opened, the bottom end of rod 23 compresses spring 24 against top washer 25, thereby cushioning the opening movement of the door. When the door is closed, the expansive force of spring 24 urges the door towards closed position to facilitate closing movement.

Although I have described a preferred embodiment of my invention in considerable detail, it will be understood that the description thereof is intended to be illustrative, rather than restrictive, as many details may be modified or changed without departing from the spirit or scope of my invention. Accordingly, I do not desire to be restricted to the exact construction described.

I claim:

1. In an oven having a front opening, a body front sheet having a relatively fixed surface surrounding said front opening, a door frame secured around the front of the oven in front of said body front sheet by means of a plurality of screws, and a plurality of set screws threaded through said door frame and engageable with said relatively fixed surface therebehind to move said door frame away from said fixed surface.

2. In an oven having a front opening, a body front sheet having a relatively fixed surface surrounding said front opening, a door frame secured around the front of the oven in front of said body front sheet by means of a plurality of screws, a plurality of set screws threaded through said door frame and engageable with said relatively fixed surface therebehind to move said door frame away from said fixed surface, and a door engaging said door frame, the meeting surfaces of said door and door frame being machined to provide a close fit.

3. In an oven having a front provided with an opening therein, a door frame secured to the front of said oven around said opening, and a plurality of screws threaded into said door frame to engage said oven front and said door frame, said screws being operable to adjust the relative spacing between said oven front and localized areas of said door frame.

4. In a cooking stove, an oven having a front provided with an opening, a door frame secured around said opening, a door hinged to one edge of said door frame, said door having a machined surface shaped to conform to said opening whereby the machined surface of said door may be positioned in face to face relationship with said door frame, a plurality of set screws threaded through said door frame and operable to adjust the spacing of said door frame relative to the front of said oven to align said door frame with the machined surface of said door, and an outer shell secured to the front of said oven and having portions cut out to permit hinged movement of said door, said outer shell concealing said set screws.

5. In an oven, a door frame comprising a casting secured to said oven, a body front sheet providing a fixed surface on said oven behind said door frame, a door hinged to engage said door frame, said door comprising a casting having an edge the same size as said door frame and engageable therewith, said castings having their meeting surfaces machined, and adjusting screws engaging said door frame and said fixed surface to bring the frame into proper alignment to form a sealing closure with said door.
